TOILET ACCESSORY

Rowland S. Carter, Los Angeles, Calif., assignor of
one-fifth to C. A. Miketta, Beverly Hills, Calif.

Application August 5, 1939, Serial No. 288,599

11 Claims.

(Cl. 4—251)

This invention pertains to an accessory for use with water closets and the like and is particularly adapted to automatically close or lower the customary toilet seat and cover whenever the water closet has been flushed. In one embodiment of the present invention the device also permits the raising of either the seat or the cover, or both, without contacting the seat or cover, the raising of these elements being accomplished by the use of the pressure ordinarily available in water supply lines.

The ordinary toilet or water closet is usually provided with a hinged seat and a hinged seat cover. Many people are meticulous in leaving the seat and cover in a lowered or closed position when not in use whereas many others are accustomed to leaving the seat and cover in a raised or elevated position, the latter class causing much mental anguish to the members of the first class. Moreover, many persons are adverse to manually handling either the toilet seat or toilet cover and resort to kicking tactics.

The present invention is directed toward an accessory or device which is readily attached to a water closet and positively insures the closure of either the seat or the cover, or both, whenever the flushing valve of such water closet is actuated. In a more advanced form of the invention a small lever or handle is provided whereby the raising of either the seat or the cover is initiated without touching the latter elements.

Generally stated, the invention comprises a housing including a pair of cylinders having pistons or plungers therein, such pistons or plungers cooperating with cams mounted upon stud shafts to which the seat and the cover are connected. The lower part of the cylinders is connected by means of a conduit with the water supply line leading to the customary flushing valve associated with such water closet. Pressure existing in the water supply line is used for the purpose of raising the seat or cover; when the flushing valve is actuated, the water pressure sufficiently drops, causing the seat and cover to slowly close. The rate of closure or lowering is regulated by suitable orifice means.

An object of the present invention, therefore, is to provide means for automatically lowering either the seat or the cover of a water closet whenever the flushing valve is actuated.

Another object is to provide means whereby the seat or cover may be raised by the aid of normally existing water pressure and without manual contact with the seat or cover.

A further object is to provide means which

automatically lower or close the seat or cover of a water closet without interfering with the normal manipulation of the same.

These and other objects, uses, advantages and adaptations of the invention will become apparent to those skilled in the art from the following description of certain illustrative forms of the invention, reference being had to the appended drawings, in which:

Fig. 1 is a perspective view of a customary water closet.

Fig. 2 is a front elevation, partly in section, of the accessory.

Fig. 3 is a horizontal section taken along the plane 3—3 of Fig. 2.

Fig. 4 is a vertical section taken along the plane 4—4 of Fig. 2.

Fig. 5 is a similar vertical section with the device in a different position.

Fig. 6 is a modified form of device in vertical section.

Fig. 7 is a vertical transverse section taken along the plane 7—7 of Fig. 6.

As shown in Fig. 1, an ordinary water closet comprises the bowl 1 provided with a seat 2 and a cover 3, the seat and cover being hinged at the back for independent movement. A water supply line, generally indicated at 4, leads to a water reservoir 5 in which there is contained a flushing valve operated by the lever 6. In some instances the water reservoir 5 is eliminated, the end of line 4 leading to a flushing valve which is in turn directly connected with the bowl 1 of the water closet. The elements just recited are old and well known in the art and need not be described in detail.

In accordance with the present invention, a device 10 is mounted to one side of the bowl 1 adjacent one end of the hinge to which the seat and cover are connected. The lower portion of the device 10 is also connected as by means of the conduit 11 with the water line 4 at a point adjacent the flushing valve 6 and on the supply side of such valve 6. In other words, the conduit 11 should not be attached to the pipe between the flushing valve and the bowl 1 but instead should be on the far side (from the bowl).

As shown in Figs. 2 to 5 inclusive, the device 10 comprises a housing containing two bores or cylinders separated as by the partition 11', each of the cylinders containing a plunger such as the plungers 12 and 13. The lower ends of the plungers may be provided with cup leathers 14 suitably held in place by means of the machine screw 15. Such machine screw or fastening

means may also suitably space the bottom of the cup leather from the bottom of the cylinders when the plungers 12 and 13 are in their lowered positions, indicated in Figs. 2 and 4.

- 5 The device 10 may also be provided with a capping member 16 suitably removably attached to the bottom portion of the housing. Stud shafts 17 and 18 may extend into the upper portion of the device and be suitably journaled therein.
- 10 These stud shafts 17 and 18 may be supported by bearings 19 and 20 formed in the upper ends of bolts 21 and 22 extending through a portion of the bowl and in the rear thereof. The two bolts 21 and 22 may be either connected or made integral with a horizontal member 23 having an extension 24 adapted to support the housing of the device 10.

As shown in Fig. 2, the stud shafts 17 and 18 are hollow tubes, the stud shaft 17 extending through both of the bearings 19 and 20 and having a filler 26 positioned therein. The stud shaft 18 is a tube rotatably mounted on the tube 17 and terminating as at 18'. The cover 3 of the water closet is connected to the shaft 17 by bracket member 27, the other bracket member of such cover 3 being indicated at 27' and being journaled upon the outer stud shaft 18. The seat 2 is provided with a pair of brackets, namely, 28 and 28', the bracket 28 being firmly attached to the stud shaft 18 whereas the bracket 28' is journaled upon the stud shaft 17.

The outer hollow stud shaft 18 terminates within the device 10 at about its mid point. Cams 30 and 31 are firmly attached to the inner stud shaft 17 and the outer stud shaft 18 respectively. It will be noted that these cams 30 and 31 are provided with a curved face 32 (Figs. 4 and 5) and a relatively flat face 33, the end of the cam being also provided with a small flat face indicated at 34. These cam means are capable of translating reciprocating movement of the plungers 12 and 13 into partial rotation of the corresponding stud shaft and hinged movement of the seat or cover or both. The flat face 34 is adapted to lock the seat or cover in closed position.

Manual means are provided for placing the plungers in operative position selectively. Such manual means may comprise a handle 36 extending through the hollow stud shaft 17 and capable of rotation therein. The handle 36 may be provided with a pin 37 extending through a slot 38 in the inner stud shaft 17. The end of the hollow stud shaft 18 may be notched as indicated at 39. The pin 37 is sufficiently long to contact with the edges of the notch 39 in the member 18.

The conduit 11 connects the supply side of the flushing valve 6 (and therefore the water supply line 4) with the bottom of the bores in which the plungers 12 and 13 are mounted and as shown in Fig. 3 relatively small channels 40 and 41 connect the conduit 11 with the bottom of these bores.

65 In the position illustrated in Figs. 2 and 4, both of the plungers 12 and 13 are at the bottom of their stroke and therefore the seat and cover are in the lowered position. By partially rotating the handle 36, the pin 37 is caused to engage the edge of the slot 38 formed in the hollow stud shaft 17 and partially rotate the same, such partial rotation moving the cam 30 into a position corresponding to the position indicated in dotted lines in Fig. 4. As soon as the cam is in 70 the slightly angled position indicated by dotted

lines, the pressure of the water from the supply line 4 and conduit 11 causes the plunger to move upwardly, such upward movement continuing until the position indicated in Fig. 5 is reached, at which time a quarter turn would have been imparted to the stud shaft 17 and the cover would now be in fully raised position. If the operator desires to also raise the seat, a slightly greater pivotal movement is imparted to the handle 36, this causing the pin 37 to contact with the edge of the notch 39 formed in the stud shaft 17 and partly rotate this stud shaft so that a similar series of movements, to those just described, is imparted to the cam 31, the seat being slowly lifted to upright position by reason of water pressure supplied by conduit 11 and port 41 to beneath the plunger 13.

As soon as the flushing valve 6 is actuated, however, rapid flow of water takes place in the line 4 through the flushing valve and into the toilet bowl 1, this causing a reduction of pressure in the conduit 11. This reduction of pressure also occurs in the space beneath the plungers 12 and 13. Spring means are provided for initiating the closure of the seat and cover, said spring means in the examples given comprising the springs 43 and 44 tending to return the cams 30 and 31 to the position indicated in Fig. 2. Such springs are only sufficiently strong to overcome the rearward tilt of the seat and cover respectively, the weight of the seat and cover being then used in rotating the stud shafts 17 and 18, in rotating the cams 30 and 31, and in depressing the plungers 12 and 13. The rapidity with which the seat and cover are lowered is controlled somewhat by the diameter of the channels 40 and 41 leading to the conduit 11. When the cams 30 and 31 return to the position indicated in full lines, Fig. 4, an increase in pressure of the fluid in conduit 11 will not raise the plungers since the flats 34 now lock the seat and cover in closed position.

In the device just described, means have been provided for selectively raising either the cover or the cover and seat by the handle means 36. 45 In the modification illustrated in Figs. 6 and 7, no such means for manually initiating the raising of the seat or cover is provided. The device illustrated in Figs. 6 and 7 is somewhat similar in that it comprises a housing 50 containing 50 bores having the plungers 51 and 52 therein, the lower portion of such bores being connected to the conduit 11 in the same manner. Cams 53 and 54 cooperate with the tops of the plungers 51 and 52 respectively, the cams 53 and 54 being firmly attached to stud shafts 55 and 56, the stud shaft 56 being hollow. The cover may be hingedly connected to the stud shaft 55 whereas the seat may be connected to the stud shaft 56. Each of the cams 53 and 54 is provided with a flat face and a curved face but no locking faces or flats are necessary. Spring means, indicated at 57 and 58, are provided for the purpose of initiating the downward movement or closure of the seat and cover. The device shown in Figs. 65 6 and 7 will automatically lower either the seat or the cover, or both, as soon as a flushing valve is actuated, but the raising of the cover or seat needs be performed by hand.

I claim:

1. In a toilet accessory for use with water closets and the like including a hinged cover, a water supply line and a flushing valve, the combination of: a cylinder containing a plunger, a conduit connecting one end of said cylinder 75

der with the water supply line on the supply side of the flushing valve, and a cam operably connected to the cover for movement therewith, said cam being in operable relation to the plunger in said cylinder, the cover, cam and plunger being adapted to move to close the cover when the pressure in the water supply line drops upon actuation of the flushing valve.

2. In a toilet accessory for use with water closets and the like including a hinged cover, a water supply line and a flushing valve, the combination of: a cylinder containing a plunger, a conduit connecting one end of said cylinder with the water supply line on the supply side 10 of the flushing valve, a cam operably connected to the cover for movement therewith, said cam being in operable relation to the plunger in said cylinder, the cover, cam and plunger being adapted to move to close the cover when the pressure 15 in the water supply line drops upon actuation of the flushing valve, and spring means operably associated with the cam for initiating closure movement of the cam and cover.

3. In a toilet accessory for use with water closets and the like including a hinged cover, a water supply line and a flushing valve, the combination of: a cylinder containing a plunger, a conduit connecting one end of said cylinder with the water supply line on the supply side of the 20 flushing valve, and a cam operably connected to the cover for movement therewith, said cam being in operable relation to the plunger in said cylinder, said cam including a face adapted to cooperate with the plunger, when the cover is 25 closed, to maintain the cover in closed position, the cover, cam and plunger being adapted to move to close the cover when the pressure in the water supply line drops upon actuation of the flushing valve.

4. In a toilet accessory for use with water closets and the like including a stud shaft, a cover attached thereto, a water supply line and a flushing valve, the combination of: a cylinder containing a plunger, a conduit connecting one end of said cylinder with the water supply line 30 on the supply side of the flushing valve, a cam carried by the stud shaft for movement therewith, said cam being in operable relation to the plunger in said cylinder, said cam including a face adapted to cooperate with the plunger, when the cover is 35 closed, to maintain the cover in closed position, the cover, cam and plunger being adapted to move simultaneously to close the cover when the pressure in the water supply line drops upon actuation of the flushing valve, and spring means cooperatively 40 associated with the cam for initiating closure movement of the cam and cover.

5. In an accessory for use with water closets and the like having a hinged seat and cover, a water supply line and a flushing valve, the combination of: a housing provided with two cylinders, a plunger in each of said cylinders, a shaft extending into said housing above said cylinders, a cam carried by said shaft above one 45 of said plungers, said shaft being attached to the water closet cover; a sleeve rotatably journaled on said shaft, a cam attached to said sleeve above the other of said plungers, said sleeve being attached to the water closet seat; and a conduit 50 connecting the bottom of each cylinder with the water supply line on the supply side of said flushing valve, the cover, seat, cams and plungers being adapted to move to close the seat and cover when the pressure in the water supply 55 line drops upon actuation of the flushing valve.

6. In an accessory for use with water closets and the like having a hinged seat and cover, a water supply line and a flushing valve, the combination of: a housing provided with two cylinders, a plunger in each of said cylinders, a shaft extending into said housing above said cylinders, a cam carried by said shaft above one 5 of said plungers, said shaft being attached to the water closet cover; a sleeve rotatably journaled on said shaft, a cam attached to said sleeve above the other of said plungers, said sleeve being attached to the water closet seat; a conduit connecting the bottom of each cylinder with the water supply line on the supply side of said flushing valve, the cover, seat, cams and plungers being adapted to move to close the seat and cover when the pressure in the water supply line drops upon actuation of the flushing valve; and spring means operatively associated with said cams for initiating closure movement 10 of the seat and cover.

7. In an accessory for use with water closets and the like including a hinged seat and cover, a water supply line and a flushing valve, the combination of: plunger means actuated by water pressure for raising said seat and cover, cam means adapted to lock said plunger means in inoperative position, manual means for moving said cam means to release said plunger means into operative position, spring means for initiating closure of the seat and cover, and orifice means for regulating the speed of closure of the seat and cover.

8. In an accessory for use with water closets and the like including a hinged seat and cover, a water supply line and a flushing valve, the combination of: plunger means actuated by water pressure for raising said seat and cover, cam means for translating movement of plunger means into hinged movement of seat and cover, 35 said cam means being adapted to lock the plunger in inoperative position when said seat and cover are closed, manual means for moving said cam means to release said plunger means into operative position, spring means for initiating closure of the seat and cover, and orifice means for regulating the speed of closure of the seat and cover.

9. In an accessory for use with water closets and the like including a hinged seat and cover, a water supply line and a flushing valve, the combination of: plunger means actuated by water pressure for raising said seat and cover, conduit means connecting said plunger means with the water supply line on the supply side of said flushing valve, cam means associated with said plunger means and adapted to lock the latter in inoperative position, manual means for moving said cam means to release said plunger means into operative position, spring means for initiating closure of the seat and cover, and orifice means in said conduit means for regulating the speed of closure of the seat and cover.

10. In an accessory for use with water closets and the like including a hinged seat and cover, a water supply line and a flushing valve, the combination of: plunger means actuated by water pressure for raising said seat and cover, conduit means connecting said plunger means with the water supply line on the supply side of said flushing valve, a cam associated with said plunger and adapted to hold the latter in locked position, manual means for moving said cam to unlock said plunger means, and spring means adapted to initiate closure of the seat and cover when the flushing valve is actuated.

11. In an accessory for use with water closets and the like including a hinged cover, a water supply line and a flushing valve, the combination of: plunger means in communication with the water supply line on the supply side of the flushing valve, a cam operably connected to said cover and in contact with said plunger means, said cam being adapted to lock said plunger

means in inactive position when said cover is closed and to permit movement of the cam by said plunger when the cam and cover are in other positions, and spring means acting on said cam for initiating closure of the cover when the flushing valve is actuated. 5

ROWLAND S. CARTER.
